UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE AND CASE.

Application filed June 16, 1920. Serial No. 389,345.

To all whom it may concern:

Be it known that I, WILLIAM F. HELMOND, a citizen of the United States, residing in Hartford, in the county of Hartford and 5 State of Connecticut, have invented certain new and useful Improvements in Typewriting Machines and Cases, of which the following is a specification.

This invention relates to shipping cases 10 for typewriting machines and means for fastening typewriting machines therein.

Cases for this purpose are ordinarily made entirely of wood, and the typewriting machines usually have their frames secured to 15 the bases of the cases by screws. These cases are likely to be subjected to considerable rough handling in transit. Such handling is apt to damage the typewriting machines within the cases, particularly the cast- 20 metal frames of the machines which are extremely brittle and are not, therefore, capable of withstanding a sudden blow of any great force.

An all-wool shipping case of this kind 25 gives no external indication of the condition of its contents, the wooden base retaining its normal external appearance so long as the case remains intact. The successive carriers and the consignee are compelled, therefore, to accept the case without 30 knowing whether or not the typewriting machine within it has been damaged.

A feature of the present invention consists in the provision of a shipping case for 35 typewriters having the usual wooden sides, but provided with a flexible sheet-metal base to which the typewriter is attached. This base is preferably pan-shaped, and is secured to the wooden walls with its concave side 40 outward. Such a base constitutes a flexible mounting for the typewriter, no matter in what position the case may be placed, and, since any blow administered to the case can be transmitted to the typewriter only 45 through this flexible metal base, the base serves to protect the typewriter frame against damage which rough handling would otherwise cause.

This base is made of sufficient strength to 50 withstand considerable rough usage. Should the case be subjected to especially severe treatment, however, of sufficient violence to damage the typewriter in spite of the protection afforded by the base, the base, having

the typewriter attached to it, will, in the majority of instances, be permanently distorted, as a result of the blow which damages the typewriter, and hence will indicate by its external appearance the probable condition of the contents of the case. 55

The typewriting machine is also subject to damage in the ordinary all-wood shipping case on account of the loosening of the 60 screws that secure the machine to the base. This loosening of the screws results in part 65 from the moisture-absorbing property of wood, which causes the wooden base to expand and contract according to the humidity of the atmosphere. This difficulty is obviated by the use of a metal base because the 70 dimensions of the metal remain uniform under varying conditions of humidity.

Another feature of the invention is the provision of means for frictionally engaging the screws which secure the typewriting 75 machine to the base, to prevent them from working loose because of vibration.

In accordance with another feature of the invention, provision is made of bosses pressed upwardly from the metal base for 80 supporting the typewriting machine spaced from the base, so as to give clearance for the typewriter parts which extend below the frame, securing screws passing through the 85 bosses for securing the typewriter to the base, and split conical washers reinforcing the bosses and frictionally retaining the screws against loosening.

Other features and advantages will hereinafter appear. 90

In the accompanying drawings.

Figure 1 is a sectional side elevation of the shipping case, taken substantially on the line 1—1 of Figure 4, and looking in the direction of the arrows at said line. 95

Figure 2 is an enlarged detail view, showing the machine frame resting on the base plate and a spring friction washer being drawn up into a recess in the base plate.

Figure 3 is a perspective view of one of 100 the spring washers.

Figure 4 is a top plan view of the shipping case with the cover removed.

Figure 5 is a perspective view of the base plate of the shipping case. 105

The shipping case or box 10 comprises two side walls 11 and 12 fastened to a front wall 13 and a rear wall 14, the joints being rein-

forced by corner pieces 15. These walls may be of boards or the like. The bottom 16 of the shipping case is made of metal, such as sheet-steel, to which a typewriter or 5 other machine 17 may be fastened by screws 18 which pass through holes 20 in the bottom or base plate 16 and are threaded into holes 21 in the machine frame 22, preferably those which receive the screws by which the usual 10 rubber feet are fastened on the frame.

The base plate is formed in the shape of a pan, which is inverted and secured at its edges 23 by screws 24 to the walls 11, 12, 13 and 14 of the case or container. The machine 15 frame 22 rests on bosses 25. These are pressed up from the body 26 of the base plate, whereby recesses 27 are formed on the under side of the base plate 16.

Since the machine frame 22 and the base 20 plate 16 are of metal and the dimensions of the metal are not affected by the humidity of the atmosphere, the tendency of the screws 18 to become loose, experienced with wooden bottoms is eliminated.

It is also desirable to prevent the screws 25 from being loosened by shaking and jarring of the shipping case. To this end, friction devices are provided to engage the screws 18. The friction devices may be in the form 30 of spring washers 28 which are inserted in the recesses 27 and under the heads of the screws 18.

The spring washers are frusto-conical and are forced into the recesses 27, which are 35 also frusto-conical, by the screws 18 which pass through holes 30 therein. Each washer is split as indicated at 31 in Figure 3, so as to allow it to contract when it is drawn up into the recess 27 by the screw. The washers 40 are thus caused to frictionally engage the heads of screws 18 to prevent the screws from shaking loose. The spring washers also serve to reinforce the portions of the base plate which form the bosses 25.

A sheet-steel cover 32 pressed into the 45 form indicated in Figure 1 is secured in place by screws 33 which enter the walls 11, 12, 13 and 14. The base plate 16 and the cover 32 may be stiffened by being corrugated as indicated at 35 and 36, respectively.

Shipping cases provided with metal tops and bottoms are considerably lighter and smaller than the usual wooden cases. They may, therefore, be shipped at less expense 55 than the wooden cases.

Variations may be resorted to within the scope of the invention, and portions of the improvements may be used without others.

Having thus described my invention, I 60 claim:

1. In combination, a typewriting machine, a shipping container therefor comprising a support, the dimensions of which are not affected by its exposure to moisture, said support having projections for supporting

the typewriting machine at a substantial distance above itself, and side walls to which the support is attached, the arrangement being such that the support is positioned intermediate the planes of the upper and lower edges of said side walls, and means attaching the support to the typewriting machine.

2. A shipping container for a typewriter, comprising a flexible metal support on 75 which the typewriter frame is secured, so as to be spaced therefrom, and board side walls to which the support is attached, so as to be positioned intermediate the planes of the upper and lower edges of said side walls. 80

3. A container comprising side walls and two ends, said walls being of wood and one of said ends being of metal, the metal end being secured to said walls, so as to be spaced 85 inwardly from the adjacent edges of said side walls, and means to support on said metal end a typewriter having a frame to be carried in said container, comprising means to space the typewriter frame from said end and fastening means effective on the 90 typewriter frame at the points where the usual feet are secured when the machine is in use.

4. A shipping case comprising wooden walls, a pan-shaped end of sheet-metal, 95 bosses pressed up from said end, said bosses serving as rests for an object to be supported thereby, and screws to pass through said bosses to fasten the object, the outer edges of said end being secured to the wooden 100 walls.

5. A shipping device comprising a support for an object, said support being in the form of a pan with a substantially flat bottom having conical recesses open on the 105 inner side of said bottom, friction devices to enter the recesses, and screws to enter the object, said friction devices serving to prevent the screws from shaking loose.

6. A base plate to support an object, said 110 base plate having conical recesses, conical washers to enter the recesses, and screws to enter the frame of the object to draw the washers into the recesses, said washers serving to prevent the screws from shaking 115 loose.

7. A base plate to support an object, said base plate having conical recesses, conical washers to enter the recesses, and screws to enter the object to draw the washers into the 120 recesses, said washers being split so as to permit them to contract when forced into the recesses by the screws, said washers serving to prevent the screws from shaking loose.

8. A base plate of sheet-metal to support 125 an object, said base plate having a conical recess, a conical spring washer to enter said recess, and a screw to enter the object to draw the washer into the recess, said washer serving to reinforce the base plate at the 130

screw and to prevent the screw from shaking loose.

9. A pan-shaped base plate to support an object, said base plate being of sheet-metal, 5 bosses pressed up from said base plate, said bosses serving as rests for the object, and screws to pass through said bosses to fasten the object to the base plate.

10. A pan-shaped base plate to support an object, said base plate being of sheet-metal, bosses pressed up from said base plate, said bosses serving as rests for the object, headed screws to pass through said bosses to fasten the object to the base plate, and devices 15 under the heads of said screws to prevent them from shaking loose.

11. A shipping case for a typewriter or like machine comprising wooden walls, a sheet-steel bottom fastened to said walls, a 20 sheet-steel bottom having conical recesses, conical washers to enter the recesses, and screws to enter the frame of the machine to draw the washers into the recesses, said washers serving to reinforce the sheet-metal 25 bottom and to hold the screws against shaking loose.

12. Means for use in shipping a typewriter comprising a pan-shaped sheet-metal support, bosses pressed out on the convex 30 side of said support, said bosses serving as rests for the feet of the typewriter, headed screws to pass through said bosses from the concave side of said support to fasten the typewriter to the convex side of the support, 35 said support having flanges extending outwardly from the edges of the opening on the concave side of the support, and side walls, each of which has one of said flanges secured thereto.

40 13. In combination, a shipping case for typewriting machines, comprising wooden side walls and a metal base, and a typewriting machine having a cast-metal frame attached to said base, said base being sufficiently flexible to yield to the momentum of the typewriting machine secured thereto when the case is roughly handled.

14. In combination, a shipping case for typewriting machines, comprising wooden 50 side walls, a metal base, and means attaching the side walls to the base, a typewriting machine in said shipping case, said machine having a cast-metal frame, and means for attaching the typewriting machine by its frame to the metal base, said base being sufficiently flexible to yield to the momentum

of the typewriting machine secured thereto when the case is roughly handled.

15. In combination, a shipping case for typewriting machines, comprising wooden 60 sides and a thin flexible metal base, said metal base being attached to the ends of the wooden sides and being generally concave on its exterior, and a typewriting machine having a cast-metal frame attached to the 65 base, said base acting as a resilient cushion for the typewriting machine in either upright or inverted position.

16. In combination, a shipping case for typewriting machines, comprising wooden 70 sides and a thin flexible metal base, said metal base being attached to the ends of the wooden sides and being generally concave on its exterior, and a typewriting machine having a cast-metal frame attached to the base, 75 said base acting as an elastic cushion for the typewriting machine to protect it in either upright or inverted position against shock due to rough treatment, and being designed to be permanently distorted by the momentum 80 of the typewriting machine body when the case is subjected to treatment of extraordinary severity, and thereby to serve as an external indication of the probable condition of the typewriting machine.

17. In combination, a typewriting machine having a cast-metal frame, and a shipping case for said machine comprising an infrangible base resiliently supporting said typewriting machine and secured to the 90 frame thereof, said base being formed to cushion the typewriting machine in any position in which the case may be placed, and to be permanently distorted without rupture by a shock of extraordinary severity. 95

18. A shipping case for typewriters comprising side walls of light rigid material, a relatively flexible metallic end wall, and fastening means for securing a typewriter within the case to said end wall thereof, said 100 end wall being arranged to receive the fastening means at points spaced substantially from the rigid walls, the arrangement being such that the end wall will act as a shock absorber to protect the typewriter against 105 the force of percussive blows to which the case may be subjected.
